CHEST

Merton L. Gershun, Martinsville, Va., assignor to
American Furniture Company, Martinsville, Va.

Application August 14, 1952, Serial No. 21,041

Term of patent 7 years

(Cl. D33—19)

To all whom it may concern:

Be it known that I, Merton L. Gershun, a citizen of the United States, residing at Martinsville, in the county of Henry and State of Virginia, have invented a new, original, and ornamental Design for a Chest, of which the following is a specification, reference being had to the accompanying drawing, forming a part thereof.

Fig. 1 is a perspective view of a chest, showing my new design;

Fig. 2 is an end elevational view of the chest of Fig. 1;

Fig. 3 is a fragmental elevational view on a substantially enlarged scale showing one end of a handle and the adjacent portion of the chest;

Fig. 4 is a fragmentary end elevational view

of the handle on the scale of Fig. 3 and a section of an adjacent chest portion.

I claim:

The ornamental design for a chest, substantially as shown.

MERTON L. GERSHUN.
